UNITED STATES PATENT OFFICE.

ROYAL A. HAWLEY, OF GRAHAM, TEXAS, ASSIGNOR OF ONE-THIRD TO J. DRIVER AND ONE-THIRD TO JOHN RUBENKOENIG, BOTH OF GRAHAM, TEXAS.

STEERING MECHANISM FOR ROAD-GRADERS.

1,308,847.

Specification of Letters Patent.

Patented July 8, 1919.

Application filed April 19, 1915, Serial No. 22,331. Renewed April 29, 1919. Serial No. 293,581.

To all whom it may concern:

Be it known that I, ROYAL A. HAWLEY, a citizen of the United States, residing at Graham, in the county of Young and State 5 of Texas, have invented certain new and useful Improvements in Steering Mechanism for Road-Graders, of which the following is a specification.

My invention has relation to a steering 10 mechanism for road graders and in such connection it relates more particularly to the arrangement and construction of a steering mechanism peculiarly adapted for use with a road grader described in a companion 15 application for patent filed by me under even date herewith and under Serial No. 22,332.

In said application for Patent No. 22,332 I have described and claimed a road grader 20 wherein the body of the machine which supports the scraping or grading blade is adjustable laterally and vertically with respect to the rear axle and also circularly or pivotally with respect to the longitudinal axis of 25 the grader and wherein the blade is supported to turn in circular bearings, supported by said body. In my present application there is illustrated and described a simple and efficient steering mechanism especially adapted for use in such a road 30 grader.

The nature and scope of my invention will be more fully understood from the following description taken in connection with 35 the accompanying drawings forming part hereof, in which,

Figure 1, is a side elevational view of the rear portion of a road scraper with steering mechanism embodying main features of my 40 invention.

Fig. 2, is a rear end elevational view of the same, and

Fig. 3, is a top or plan view thereof.

Referring to the drawings, 1, represents 45 the body of the machine and 2 the scraper blade suspended from the body 1 and turning in the annular bearing 3. The rear end of body 1 is supported on a circular bearing 4 which is carried by the rear axle 5. The 50 construction and arrangement of all these parts are more particularly described in my

companion application for Patent Serial No. 22,332.

For the sake of clearness certain portions of the construction of the rear bearing have 55 been eliminated in the drawings of the present application. The rear axle 5 is box-shaped and hollow with the upper and lower slots 6. This or a similar construction of axle 5 is prescribed by reason of the fact 60 that it is desirable to support the rear bearing 4 so that it may slide or move laterally on the axle 5, as clearly explained in said application No. 22,332.

The top and bottom of the axle 5 are extended at the extreme ends to form at each end a frame or bracket 7 in which a vertically arranged shaft or pintle 8 is pivotally supported. From the shaft or pintle 8 projects radially a stub shaft or axle 9 on each 70 of which a wheel 10 of the machine turns. From the periphery of each pintle 8 also projects a short arm 11 and the two arms 11 are connected by a rod 12 preferably extending parallel with the rear face of the axle 5. 75

From preferably the top of axle 5 and to the rear of the same, extends a platform 13 on which is mounted, preferably at the middle portion, a sector gear 14. A hand lever 15 connected at its lower end to rod 12 80 and pivoted to the sector gear 14, carries a pawl 16 working over the teeth of gear 14 and controlled by the hand lever 17.

When pawl 16 is released from the gear 14, the hand lever 15 may be shifted in either 85 direction on its pivotal support and the rod 12 will be shifted to right or left to throw the wheels 10 to their proper angular relationship to the body of the machine to turn the machine. The steering mechanism thus 90 described is simple and is so constructed and arranged that it will not interfere with the proper adjustment of the rear bearing for the body either in vertical or lateral planes or in circular planes if required.

Having thus described the nature and objects of my invention what I claim as new and desire to secure by Letters Patent, is,—

In a steering mechanism for road graders, a box-like hollow axle, a bracket formed at 100 each end by projecting the top and bottom faces of said axle, a vertically arranged

pintle pivotally supported in each bracket, a stub axle projecting radially from each pintle, an arm carried by each pintle and a rod connecting the arms, combined with a platform supported by the top of the hollow axle, a hand lever, locking pawl and a sector gear mounted upon said platform, said hand

lever pivoted intermediate of its ends to said sector gear and having its lower end connected with said rod, said lever swinging about its pivotal support in a vertical plane.

In testimony whereof I have signed my name to this specification.

ROYAL A. HAWLEY.
